UNITED STATES PATENT OFFICE.

WILLIAM T. ROOK, OF CHEYENNE, OKLAHOMA TERRITORY.

MAIL-BAG CATCHING AND DELIVERING MECHANISM.

No. 818,470.

Specification of Letters Patent.

Patented April 24, 1906.

Application filed July 31, 1905. Serial No. 272,105.

To all whom it may concern:

Be it known that I, WILLIAM T. ROOK, a citizen of the United States, residing at Cheyenne, in the county of Roger Mills, Oklahoma Territory, have invented certain new and useful Improvements in Mail-Bag Catching and Delivering Mechanisms, of which the following is a specification.

This invention embodies novel mechanism for catching and delivering mail-bags, and includes combined means carried both by rolling-stock and by a stationary support at one side of the track over which such rolling-stock passes for catching the mail-bags and simultaneously delivering the bags to the train as it is in motion.

The essential feature of the invention resides in the special means employed for delivering the bags to the car, such mechanism being adapted to automatically receive the bag from the stationary support or deliverer at one side of the track and carry the load into the body of the car convenient for removal of the contents thereof by those handling the mail.

For a full description of the invention and the merits thereof and also to acquire a knowledge of the details of construction of the means for effecting the result reference is to be had to the following description and accompanying drawings, in which—

Figure 1 is a perspective view showing a car and a stationary support embodying the mechanism constituting this invention. Fig. 2 is a side elevation illustrating a car approaching the stationary deliverer and catcher, showing the bag-holders preparatory to being delivered to and removed from the stationary deliverer and catcher. Fig. 3 is a view similar to Fig. 2, the bag-holder supported by the car in Fig. 2 having been delivered to the stationary catcher and deliverer and the other bag-holder supported by the stationary deliverer and catcher in Fig. 2 being shown caught by the mechanism on the car. Fig. 4 is a transverse section of the car, broken away, showing more clearly the form of the movable support carried thereby and designed to catch and deliver the mail-bag. Fig. 5 is a top plan view showing the car broken away and bringing out more clearly the arrangement of the parts of the extensible or movable support carried by the car. Fig. 6 is a perspective view of one of the bag-holders. Fig. 7 is a vertical section of the stationary deliverer and catcher.

Corresponding and like parts are referred to in the following description and indicated in all the views of the drawings by the same reference characters.

Referring to the drawings and specifically describing the invention, the numeral 1 designates a car, which may be the customary mail-car, and said car has mounted thereon a movable or extensible support, which consists of an inclined rail 2, which may be of a length nearly equal to the width of the car, and this inclined rail is provided at its outer end, exterior of the car 1, with a vertical standard 3. The vertical standard 3 is formed at its upper end with laterally-projecting arms 4, one extending forwardly and one rearwardly longitudinally of said car. The arms 4 are adapted to support a bag-holder when the car is moving in either direction preparatory to delivery of such holder to the stationary catcher located at one side of the track, as shown in Fig. 1. Standard 3 of the movable support, of which it forms a part is braced with reference to the car by means of extensible braces 5, which comprise telescoping sections, one of said braces 5 being pivotally connected with the car at the upper portion thereof, the opposite end of the braces being similarly connected at the upper end of the standard 3, as shown at 6. The inner end of the rail 2 is curved upwardly, as shown at 7, and is formed with a loop 8, receiving a transverse supporting-bar 9, the ends of which are suitably attached to the sides of the car interior of the latter. The member 8 affords a sliding connection between the rail 2 and the bar 9, and said bar 9 virtually forms a track upon which the member 8 is adapted to slide as the rail 2 is projected wholly into and extended out of the car in actual conditions of service. When arranged in the car, the rail 2 assumes an approximately horizontal position as the bar 9 is curved downwardly near one end, as shown at 10, the downwardly-curved portion 10 being adapted by engagement with the member 8 of the rail 2 to firmly hold said rail projected from the car, as shown in Figs. 1 and 4, and inclined from the horizontal. When the rail 2 is pulled inwardly into the car, as shown in dotted lines in Fig. 4, the member 8 thereof rides up the curved portion 10 of the bar 9, and this raises the rail to the horizontal position before mentioned. The movable support, which includes the rail 2 and the catching and delivering arms 4, is braced also by

means or a connection 11, one end of which is connected with the upper end of the standard 3, the opposite end having a slidable connection with the bar 9. The connection 11 coacts with the braces 5 and the member 8 to rigidly hold the rail 2 in the inclined position shown in Fig. 4 preparatory to delivering or catching a mail-bag while the car is in motion.

As is customary in devices of the type described herein, a stationary catcher and deliverer is located at one side of the track over which the rolling-stock passes, and in this instance this means consists of the stationary supporting-post 12, having a vertically-adjustable section 13 and an adjusting-screw 14 to hold said section 13 at a suitable vertical adjustment to enable the catching and delivering arms 15 thereof to be properly placed in operating to deliver or catch the mail-holder supported on cars of different sizes.

The catching and delivering supports located on the car and at the side of the track are adapted to cooperate with a special form of mail-holder which directly supports the mail-bag. The mail-bag holder is indicated at 16 and consists of a trolley embodying a suitable frame, at the upper portion of which is mounted a trolley-wheel 17, the lower portion of the frame being formed with a mail-bag-supporting member 18. The member 18 preferably forms a part of the frame of the holder 16 and is of somewhat circular form, as shown most clearly in the drawings. The frame-holder 16 is provided with 8 openings 19 between the trolley and the member 18, and these openings are designed to receive a catching and delivery arm 15 of the stationary catcher and deliverer when the mail-holder is supported thereon preparatory to being delivered to the car by being caught by the mechanism carried by said car. Spaced guide-arms 20 project laterally from the frame of the mail-bag holder 16, and these guide-arms diverge toward their outer extremities, the space between said arms leading to the space below the trolley-wheel 17 of the holder. An automatically-operating latch 21 is pivoted to the outer extremity of the upper of the arms 20, as shown at 22, and the lower end of said latch is limited in its outward movement by the stop 23 at the outer extremity of the lower arm 20, said stop consisting of the integral extension of said arm. When the mail-bag holder 16 is supported by the delivery mechanism on the car, the trolley-wheel 17 forms the connecting means for holding the holder 16 in position, and for this purpose said trolley-wheel is formed with a lateral opening 24 adjacent its periphery, said opening being adapted to receive either of the arms 4 when the holder is supported thereby.

Referring to Figs. 2 and 3, the car is shown approaching from the direction of the arrow,

the catching and delivering mechanism of said car being in operative position, such as shown in Fig. 5, the bag-holder 16 being supported by the arm 4, which is remote from the stationary catcher and deliverer with regard to the direction of travel of the car. The mail-bag holder 16, which is carried by the arm 4 before mentioned, is to be delivered to the stationary catcher and deliverer, and said stationary catcher and deliverer has a bag-holder 16 mounted on the arm 15 which is remote from the delivery mechanism on the approaching car. As soon as the car reaches the stationary catcher and deliverer the nearer arm 15 thereof, passing through the member 18 of the bag-holder 16 of the car, disengages said bag-holder from the arm 4, supporting the same, and the mail-bag and holder 16 are delivered to said arm 15 of the stationary catcher. Meanwhile the car as it progresses has carried the inclined rail 2 to the mail-bag holder 16, which is supported on the remote arm of the stationary catcher and deliverer, and said rail 2 is forced between the guide-arms 20 of the said mail-bag holder 16 tripping the latch 21 thereof. The member 20 guide the rail 2 and the trolley-wheel 17 and as the rail 2 forces the bag-holder off of the arm 15, supporting the same, the holder is thrown upon the rail 2, and the trolley-wheel 17 engages said rail, so that the bag-holder will travel down the rail 2 to the interior of the car. When said holder 16 has been delivered to the car, as above described, the rail 2 and the movable support of which it forms a part may be pulled inwardly into the car by means of a suitable operating-rod (not shown) or any other means, and said rail 2 will assume a horizontal position and permit the bag-holder 16 to be moved therealong or to be entirely removed therefrom, according to the desire of the operators in the car. In the actuation of the rail 2 engaging the bag-holder 16 as the latter is delivered to the car the latch 21 as soon as the rail engages the trolley-wheel 17 falls back by gravity against the stop 23 and prevents the jar or vibration in the delivering operation from jarring the trolley or bag-holder 16 from the track-rail 2.

It is contemplated that the catching and delivering mechanism of the car shall comprise two of the movable supports shown in the drawings, so that the rails 2 may be projected from either side of the car under actual conditions of service.

It is designed that each of the arms 4 may be provided with a spring attached thereto in any substantial way so as to pass through the opening in the wheel 17 when the holder 16 is disposed upon one of the arms. The spring will so engage the holder as to hold the same properly in place.

Having thus described the invention, what is claimed as new is—

1. In combination, a car, a mail-catcher

130

including a mail-receiving support mounted on the car and inclining upwardly from a point interior of the car to a point exterior thereof, and a bag-holder to be received upon the inclined support and to gravitate into the car thereon.

2. In combination with a car, a mail-bag catcher carried by the car and embodying an inclined rail, and a bag-holder consisting of a trolley adapted to be received on the inclined rail and to travel into the car thereon.

3. In combination with a car, a mail-bag catcher carried by the car and embodying an inclined rail, and a bag-holder consisting of a trolley adapted to be received on the inclined rail and to automatically travel into the car thereon.

4. In combination with a car, a mail-bag catcher embodying a rail supported by the car, and a mail-bag holder to be caught by said rail and embodying a trolley adapted to travel thereon.

5. In combination with a car, a mail-bag catcher embodying a rail supported by the car, a mail-bag holder to be caught by said rail and embodying a trolley adapted to travel thereon, and means carried by the trolley for preventing accidental displacement thereof after it is delivered to the rail.

6. In combination with a car, a mail-bag catcher embodying a rail supported by the car, a mail-bag holder to be caught by said rail and embodying a trolley adapted to travel thereon, and an automatically-operated latch for preventing displacement of the trolley or bag-holder from the rail after it has been delivered thereto.

7. In combination with a car, a catcher

mounted thereon and embodying an inclined rail, a mail-bag holder consisting of a trolley to be delivered to the inclined rail, and an automatically-operating device carried by the trolley for preventing accidental displacement thereof after it has been delivered to the rail.

8. In combination with a car, a movable support mounted thereon and including a movable rail adapted to be projected from the car and upwardly and outwardly inclined in position when so projected, and a mail-bag holder embodying a trolley to be delivered to the rail to travel into the car thereon.

9. In combination with a car, a mail-bag catcher mounted thereon and embodying a supporting-rail, a mail-bag holder consisting of a trolley to be caught by said rail and to travel thereon into the car, and a trolley-wheel for the trolley adapted to support the mail-bag holder preparatory to delivery thereof from the car.

10. In combination with a car, a mail-bag catcher thereon embodying a supporting-rail, a mail-bag-supporting member independent of said rail, a mail-bag holder consisting of a trolley adapted to be caught by the rail aforesaid and to travel thereon, and means carried by said trolley whereby the same may be supported upon the supporting member aforesaid preparatory to delivery thereof from the car.

In testimony whereof I affix my signature in presence of two witnesses.
